DESIGN FOR A WOVEN TEXTILE FABRIC

John L. Walther, New York, N. Y.

Application May 14, 1936, Serial No. 62,635

Term of patent 3½ years

To all whom it may concern:

Be it known that I, John L. Walther, a citizen of the United States of America, residing in city of New York, county of New York, and State of New York, have invented a new, original, and ornamental Design for a Woven Textile Fabric, of which the following is a specification, reference being had to the accompanying drawing, forming part thereof.

In the drawing the sole figure is a plan view of

a piece of the woven textile fabric embodying the design of the present invention.

The design is characterized by a series of thick and thin, dull and lustrous multi-colored yarns arranged on a hairy background giving a lattice-like appearance to the fabric.

I claim:

The ornamental design for a woven textile fabric, substantially as shown and described.

JOHN L. WALThER.
